[57] CLAIM

The ornamental design for a retractable marine thrust motor, substantially as shown and described.

DESCRIPTION

FIG. 1 is a top, front and left side perspective view of a retractable marine thrust motor showing my new design in the retracted position;

FIG. 2 is a rear elevational view thereof;

FIG. 3 is a bottom plan view thereof;

FIG. 4 is a side elevational view thereof, shown in the extended position;

FIG. 5 is an opposite side elevational view thereof, shown in the extended position; and

FIG. 6 is a top, front and left side elevational view thereof, shown in the extended position with a portion broken-away for clarity of illustration.

FIG.1.

FIG.2.

FIG.3.

FIG. 4.

FIG. 5.

FIG. 6.
